UNITED STATES PATENT OFFICE

2,583,432

FOUNTAIN PRESSURE SUPPLY CAR WASHER

Bernard Leverock, Lynbrook, N. Y.

Application May 19, 1949, Serial No. 94,069

2 Claims. (Cl. 15—130)

1

This invention pertains generally to fountain type washers, and it relates particularly to a car washer; and the general object of my invention is an inexpensive and practical fountain washer particularly adapted to the washing and cleaning of cars.

I have invented a fountain washer for cars that is both practical and economical. My fountain washer is so formed as to be capable of manual operation without attachment of any cumbersome handle. This washer has a sponge bottom and a hard rubber body, so that it can be roughly handled, dropped, and generally used without fear of scratching or marking the car.

My washer has a quadrilateral shaped sponge bottom, which enables it to get into corners and out of the way places where a handled brush could not possibly go.

The body of this washer is hollow, broad at the base, and tapered at the top, as a result of which a compression chamber is effected within the body of my washer whereby a forceful spray can be obtained for softening stubborn dirt particles. A secondary dripping of water is provided whereby dirt loosened by the spray is washed away by the water dripping through the sponge.

Another object of this invention is a fountain car washer having a forceful spray surrounded by a heavy dripping of water.

A further object of this invention is a fountain car washer operable without handle, that can clean in corners, and can be generally handled without fear of scratching the car being cleaned.

A still further object of my invention is a fountain car washer provided with a water compression chamber.

Other objects and advantages of my invention together with its structural details will be apparent from the following description when read in conjunction with the accompanying drawings, wherein a specific embodiment of my invention is illustrated, and wherein,

Fig. 1 is a top plan view of the invention,

Fig. 2 is a side elevation view with part cut away to show the relative arrangement of the parts,

Fig. 3 is a bottom plan view,

Fig. 4 is a plan view of the spray plate,

Fig. 5 is a rear elevation view, and

Fig. 6 is a front elevation view.

Fig. 7 is a sectional view taken midway in Fig. 2 and cutting completely through such figure.

In the drawings is shown a housing or hollow body 1 provided with a broad quadrilateral base

2

2 and an arched, narrowed or tapered gripping upper portion 3. The hollow body 1 opens through to the outside both at its base end 4 and at its top end 5. The body 1 is preferably of hard rubber construction because of the purpose for which it will be used, so as to prevent scratching and marking of the car being washed. The base 2 is substantially rectangular with slightly rounded corners 6 whereby the device is enabled to get into corners and out of the way places. About the interior walls 7 of the base is a marginal shoulder 8. On to this shoulder there is attached by suitable means, such as rubber cement, a hard rubber plate 9, which plate also has its corners 6' rounded in conformity with those of the base 2. Centrally of this plate is a group of spray holes 10. Bordering the plate 9 is a series of holes 11 slightly larger in diameter than the spray holes 10. Attached to the bottom of the rubber plate 9 by suitable means, such as rubber cement, is a sponge 12 the corners 6'' of which are also rounded to conform with those of the plate 9 and the base 2. Centrally of the sponge section 12 is a cut-out 13 communicating with the group of spray holes 10 of the plate 9. The sponge 12 is preferably of soft rubber and serves to emit water to, and to contact the surface to be cleaned. The base 2 narrows gradually upwards to form the arched tapered upper structure 3. The upper structure in the nature of a handle can be gripped by hand, and serves to permit a scrubbing movement of the device. The upper structure 3 is arched to allow for a secure hand grip of the device, and to thereby prevent slipping of the hand from the rubber body 1 as it becomes wet. About the opening in the top end 5 of the body 1 is a shoulder 14. Suitable water hose connecting means 15 is adapted to fit in the open top end 5. This hose connecting means has a water hose engaging coupling 16 provided with an extended lower portion 17, which extension is insertable through the open top end 5. Washers 18 on the coupling extension 17 limit against both sides of the top opening shoulder 14. The coupling 16 limits against the outer washer 18. Threadable on to the extension 17 on the inner side of the device is a securing nut 19 adapted to limit against the inner washer 18 and to securely hold the hose connecting means 15 in the top end 5. It is to be noted, as it is a very important feature, that the base 2 of the device is larger in area than its tapered upper structure 3. This construction creates a compression chamber, and enables a water pressure to build up within the hollow

body 1 and the water to be forcefully sprayed through the holes 10. The combination of the central spray holes 10 with the cut-out 13 in the sponge 12 in communication with such holes, together with the wider border holes 11 in the plate 9 is also an important aspect of this device. The cut-out in the sponge enables a spray through the spray holes 10 to be emitted forcefully and unimpeded; the larger holes 11 permit water to drip through and throughout the sponge.

The manner of use and operation of the device is obvious from the above and the drawings. The device is by means of the coupling 16 connectable to a garden water hose, and is particularly adapted to and useful in the cleaning and washing of automobiles.

The form described above is not to be construed as a limitation of my invention, for it is my intent to claim all that is reasonably within the spirit of the invention and within the scope of the appended claims.

I claim:

1. A fountain pressure supply car washer of the character described, having a hard rubber body portion open at its base and top ends, a chamber within said body in communication with the top and base openings, said base end of said body portion being substantially square with a marginal shoulder about such base end, an upper handle portion arched and tapering from said base end for gripping purposes, said chamber being substantially square at its base and tapering at its upper portion, a base plate of hard rubber covering said base opening and having its outer edges cemented to the said marginal shoulder of the base end, a group of spray holes centrally of such base plate, a series of holes larger than the spray holes located about the border of the base plate, a rubber sponge conforming to the dimensions of the base plate and cemented thereto, said rubber sponge having a central cut-out in communication with only the spray holes, and a shoulder about the top end opening of the body portion adapted to support hose connecting means.

2. In a fountain pressure supply car washer, a hard rubber body portion open at its base and

top ends, a pressure chamber within said body in communication with the top and base end openings, said base end of said body portion being substantially square with a marginal shoulder about such base end, an upper handle portion arched and tapering from said base end for gripping purposes, said pressure chamber being substantially square at its base and tapering at its upper portion, a base plate of hard rubber covering said base opening and having its outer edges cemented to said marginal shoulder of the base end, a group of spray holes centrally of such base plate, a series of holes larger than the spray holes and located about the border of the base plate, a sponge conforming to the dimensions of the base plate and cemented thereto, said sponge having a central open section in communication with the spray holes, and a shoulder about said top end opening of the body portion adapted to support hose connecting means, said sponge covering the whole of said base plate with the exception of the spray holes whereby water passing through said pressure chamber of the body portion is permitted to drip through the sponge from the larger plate holes and is permitted to be sprayed forth through the spray holes.
